US0D1082260S

(12) **United States Design Patent** (10) Patent No.: **US D1,082,260 S**
(45) Date of Patent: ** Jul. 8, 2025

(54) **SOLE**

(71) Applicant: **Rongfang Lin**, Nanping (CN)

(72) Inventor: **Rongfang Lin**, Nanping (CN)

(**) Term: **15 Years**

(21) Appl. No.: **29/989,899**

(22) Filed: **Feb. 18, 2025**

(51) LOC (15) Cl. **02-04**

(52) U.S. Cl.

USPC **D2/947**; D2/951; D2/960
